WEB WINDING

Oscar C. Reesen, Scarsdale, N. Y., assignor to
Wood Newspaper Machinery Corporation,
Plainfield, N. J., a corporation of Virginia

Application July 16, 1943, Serial No. 494,968

16 Claims. (Cl. 242—56)

This invention relates to web rolls and more particularly concerns an improved method of and apparatus for winding successive rolls from a continuous web of relatively thin flexible material such as paper, fabrics, or the like.

Large web rolls are customarily wound from the web issuing from a paper- or other web-making machine, or from web drawn from a master roll. To expedite this operation, it is necessary that when a given roll is completely wound, the continuous web running to it be severed and the severed end started around a core to wind another roll, and this should be accomplished without stopping or materially retarding the movement of the web. Previously known methods and apparatus for performing operations of this nature have been complicated or uncertain and it is the object of the present invention to provide an improved and simplified method and apparatus for simultaneously severing the web running to a roll and starting the severed web end around a core to commence winding another roll, all while the web is traveling at full speed. Another object of the invention is to provide a method and apparatus of this nature in which the web is severed so close to the point thereon where it is started around the new roll core that no appreciable backfold or tail is left at the core surface. The method and apparatus of the invention is also useful in applying a layer of adhesive to an area of the web adjacent its core end while the web is being wound. Such an adhesive layer is useful in splicing the core end of the web to the leading end of the web on a new roll so as to continuously feed web from successive rolls to a printing press or other web consuming apparatus, as for example, in accordance with the method disclosed and claimed in my Patent No. 2,320,656 entitled "Web roll changing."

In general, the above and other objects of the invention are carried out by running the continuously moving web being wound into a roll over a surface or support as it approaches the roll, bringing a rotatably supported roll core into contact with the moving web whereby the core is accelerated to web speed, positioning a knife or other web severing member adjacent the surface of the web moving away from the rotating core and at a point close to the core surface, and then applying adhesive to the core or to the core contacting surface of the web approaching the core, whereby a section of the web is stuck to and lifted by the core and the web traveling beyond the core toward the completed roll is moved against the knife and severed thereby. This ap-

plication is a continuation in part of my copending application Serial No. 482,586, filed April 10, 1943, entitled "Web splicing."

The invention will be best understood by reference to the accompanying drawing where certain embodiments thereof have been illustrated. In the drawing:

Fig. 1 is a diagrammatic elevation of web roll winding apparatus embodying my invention and capable of performing my method;

Fig. 2 is an elevation of the roll winding apparatus of Fig. 1 at the instant that the web is being started on a new core;

Figs. 3 and 4 are elevations illustrating the operation of the roll winding apparatus in transferring a newly started core to the roll winding position;

Fig. 5 is a fragmentary elevation illustrating a modified arrangement of the adhesive applying means; and

Fig. 6 is a view similar to Fig. 5 showing the application of adhesive to the core rather than to the web.

Referring to Fig. 1, 6 represents a web of paper or any other relatively thin flexible material which may, for example, comprise the paper web issuing from the final calender of a paper-making machine. The web 6 travels around a guide roll 7, through a drying oven 8 where it is supported by suitable means such as the rollers 9, under a guide roll 10 to a roll winding device designated as a whole as R.

The roll winding device R winds the web 6 into a succession of web rolls of the desired size, and the present invention has to do primarily with an improved means and method for transferring the traveling web from a fully wound roll to a core to start the winding of a new roll. The winding device shown in the illustrated embodiment is in some respects similar to the device generally known in this art as a Pope rewinder, one form of which is shown in the Pope Patent No. 1,248,542, dated December 4, 1917.

The device R shown includes an under roll or drum 11, journaled in a frame 12 and suitably driven at such a speed that its peripheral velocity is equal to or very slightly greater than the velocity at which the web 6 is delivered from the paper-making machine or other source. Two parallel roll arms, one of which is shown at 13, are pivotally connected to the frame 12 to swing about the axis of the drum 11, one of the arms being adjacent each end of the drum. The arms 13 are preferably rigidly connected by suitable means to move in unison about their pivots. The

upper ends of the arms are bifurcated as shown at 14. The arms 13 extend downwardly beyond the pivot point and are releasably engaged at their lower ends by a suitable yielding support. As shown, this support may comprise a rod 15 having the angularly bent end removably secured in a notch 16 at the lower end of the arms 13, the rod being slidably carried in a tubular member 17 that is pivotally supported at 18. A spring 19 resists movement of the rod 15 into the tubular member 17. The yielding support may be provided in duplicate with one unit for each arm of the pair 13. It will be apparent that with this arrangement, the arms of the pair 13 may move to a limited extent about the axis of the drum 11 in the direction of rotation of the drum as indicated by the arrow, but are normally maintained in the position shown. Also, by moving the rod 15 out of engagement therewith, the arms 13 may be freely moved about their pivots.

Another pair of parallel rigidly connected roll core arms 19 is provided for carrying the rolls in the winding position. As shown, the arms 19 are pivotally secured to the frame 12 near the end thereof toward which the web moves, and the ends of the arms are bifurcated as shown at 20 to receive roll core journals. Two roll cores 21 and 22 successively cooperate with the drum 11 to wind the web rolls. The cores 21 and 22 have journals 23 and 24, respectively, which fit the bifurcated ends 14 and 20 of the arms 13 and 19. A knife or other web severing means 25 is carried by a suitable frame 26 pivoted to a fixed shaft 27. When the support 26 is lowered as shown to a position fixed by the adjustable stop 28, the knife 25 extends transversely across and close to the upper surface of the web 6 where it leaves the roll core 21. In this position, the knife 25 is close to the surface of the core 21. The pivoted support permits movement of the knife 25 to a retracted position when it is desired to move or change the roll core 21, as shown in Fig. 3.

Suitable yielding tension means are provided for permitting limited variations in the speed of travel of the web 6 approaching the drum 11. In the disclosed embodiment, this takes the form of a yieldably mounted roller 29 engaging the upper surface of the web 6 where it approaches the drum 11. As shown, the roller 29 may be carried in slidably mounted journal boxes 30 that are biased by the springs 31 to the position shown in Fig. 1. When the web 6 on the drum 11 is momentarily accelerated as an incident to shifting it to a new roll core as hereinafter described, the roller 29 rises against the force of the springs 31 to permit shortening of the span of the web, as shown in Fig. 2, and tearing or stretching of the web may be thereby avoided. When the web material is extensible without breakage or injury, the yielding tension means described may be dispensed with.

Suitable means are provided for applying adhesive to the roll core contacting surface of the web 6 approaching the drum 11. The adhesive applied may be an ordinary tacky adhesive such as rosin glue or any other suitable known glue or paste. In accordance with one aspect of the invention, the adhesive applied is a self-sticking adhesive of the type described in detail in my Patent No. 2,320,656. This type of adhesive, which will be hereinafter referred to as a self-sticking adhesive, is of the nature of a rubber cement. As explained in my aforesaid application, this self-sticking adhesive has the property

of adhering tenaciously to the paper or other web when applied thereto in liquid form and dried thereon, but when dried its exposed surface does not adhere to an uncoated web or other surface. The dried self-sticking adhesive coatings cohere tenaciously with similarly applied and dried coatings, so that when two surfaces bearing such coatings contact each other they are firmly stuck together.

Adhesives of either conventional or self-sticking type may be applied by any suitable means to the core contacting surface of the web 6 before it reaches the core 21 or to the surface of the core. As shown in Fig. 1, adhesive may be sprayed from a container 32 through a slot or nozzle 33 extending transversely of the upper surface of the web 6, the flow of adhesive being controlled by suitable means such as the valve 34. When a self-sticking adhesive is so applied, it may be dried on the web surface by passing the coated web through a suitable oven 8 which may be heated by hot air currents, electrical heating elements or any other known means. When ordinary tacky adhesive is used, the oven 8 may be dispensed with or the heat supply thereto turned off. The self-sticking adhesive may be used in a form employing a very volatile quick-drying solvent, in which case the oven 8 may be omitted and the adhesive applied to the upper surface of the web 6 at any desired point sufficiently remote from the roll core 21 to permit drying of the adhesive between the point of application and the roll core. Such an arrangement has been illustrated in Fig. 5, where the adhesive is sprayed from a container 35 through a nozzle 36 under control of a valve 37 at approximately the point where the web 6 first engages the drum 11. Ordinary tacky adhesive may be applied to the surface of the roll core 21 rather than to the surface of the approaching web. This arrangement has been illustrated in Fig. 6, where adhesive is sprayed from a container 45 through a nozzle 46 under control of a valve 47 onto the surface of the core 21 approaching the upper surface of the web 6 passing under the core.

When ordinary tacky adhesive is used, it may, of course, be applied to the web at any point in its travel prior to that at which the web passes under the core 21.

The operation of the disclosed embodiment of my improved apparatus in carrying out my method will now be described. The web 6 runs over the rotating drum 11 and is wound into a roll 38, the core 22 of which is supported by engagement of its journals 24 with the bifurcated ends 20 of the arms 19. In this position, which is herein termed the roll winding position, the roll 38 is propelled in the direction indicated by the arrow by surface contact with the rotating drum 11. While the roll 38 is being wound, a new roll core 21 is placed in the starting position as shown in Fig. 1 with its journals 23 held in the bifurcated ends 14 of the arms 13. When a self-sticking adhesive is employed, the entire cylindrical surface of the core 21 bears a dried coating of this material as indicated at 39. If ordinary tacky adhesive is used no adhesive layer is carried by the core 38. The knife frame 26 is lowered to the position shown in Fig. 1 after the core 21 is in place. The cylindrical surface of the core 21 rests on the web 6 traveling on the driven drum 11, and the core is accordingly accelerated such that its peripheral velocity equals the web speed.

When the roll 38 in the winding position has reached the desired size, the operator merely

applies a layer of adhesive to the surface of the core 21 or to the upper or core contacting surface of the web 6 before it reaches the core 21. This may be accomplished by opening the valve 34 for a suitable interval. When a self-sticking adhesive is employed, it may be dried in the oven 8 or, if it is dissolved in a highly volatile solvent, it may dry in the atmosphere and may be applied with either the arrangement of Fig. 1 or that of Fig. 5. A tacky adhesive may be applied to the core 21 as illustrated in Fig. 6. When the section of the web bearing the applied adhesive passes under the roll core 21, or the adhesive bearing surface of the core contacts the web, the web is stuck to the core and continues around its cylindrical surface so that the span of the web between the roll core 21 and the roll 38 is lifted off of the surface of the drum 11, as shown in Fig. 2. This moves the web 6 into the knife 25 and severs the web close to the surface of the core 21. The web end is accordingly carried around the core 21 and the winding of a new roll on this core is thus started.

Instead of applying the adhesive directly to the web surface, it may be applied by sticking a prepared sheet bearing the adhesive to the upper surface of the web 6 as it approaches the roll winding apparatus E. The prepared sheet thus applied may bear either conventional or self-sticking adhesive on its outer surface and may be stuck to the web by ordinary tacky adhesive. Apparatus suitable for so applying an adhesive bearing sheet to a moving web and a method for performing this operation are described and claimed in my copending application Serial No. 414,274, filed October 9, 1941, entitled "Application of prepared adhesive to webs."

When self-sticking adhesive is employed, the uncoated upper surface of the web 6 passing under the core 21 does not stick thereto because of the above described properties of the dried self-sticking adhesive layer 39 on the core surface, but as soon as the applied and dried layer of this adhesive on the web 6 contacts the layer 39 on the core 21, the web is firmly stuck to the core. The arrangement of the knife 25 close to the surface of the core 21 insures that the web 6 is cut close to the point where it is stuck on the core surface, and no appreciable end or tail of the web is left to form a backfold and so disturb the even winding of the web on the core.

The lifting of the web between the new core 21 and the roll 38 tends to both momentarily accelerate the web approaching the core 21 and shorten the web span between the roll 38 and the core 21. When the web material is extensible it merely stretches over this span. With inextensible webs, breakage or injury is avoided by movement of the core 21 circumferentially of the drum 11 in the direction of web travel against the bias of the springs 18 and by yielding of the tension roller 29, as shown in Fig. 2 and described above.

After the web 6 has started around the new core 21, the completed roll 38 is removed from the arms 13, the yielding support is disconnected from the arms 13 by moving the end of the rod 15 out of the notch 16 as explained above, and the arms 13 are swung in the direction of web travel until the journals 23 of the core 21 rest in the bifurcated ends 20 of the arms 13 as shown in Fig. 3. This transfers the core 21 to the winding position, and as the new roll 40 builds up, the core journals 23 are lifted out of the bifurcated ends 14 of the arms 13, whereupon these arms may be

returned to the starting position ready to receive the next roll core, as illustrated in Fig. 4.

When the web being wound is to be employed in splicing operations such as that described and claimed in my aforesaid application Serial No. 403,515, now Patent No. 2,320,656, it is necessary that a layer of self-sticking adhesive of considerable extent be applied to a section of the web at the core end of each roll. As explained in my aforesaid application, this layer of adhesive should extend longitudinally of the web by a distance at least equal to the circumference of the largest new web roll employed. The method and apparatus of the present invention are particularly useful in preparing webs of this nature. The required core end layer of self-sticking adhesive may be easily applied by merely continuing the application of this adhesive to the web for an interval such that the required length of web is coated. The leading end of this coating acts as has been described to cause the severing of the web and the starting of its end around a new core. A length of coated web equal to the circumference of the web roll core is consumed for this purpose, and the remainder of the coated section of the web constitutes the core end self-sticking adhesive layer that acts in the web splicing method of my aforesaid invention.

I claim:

1. The method of transferring a moving flexible web running to a web roll being wound to a core to start the winding of another web roll which comprises bringing a rotatable roll core into contact with the surface of the web running to the roll whereby the core is accelerated to web speed, positioning a knife across the web adjacent the core contacting surface of the web where it leaves the core, and applying adhesive to the core contacting surface of the web approaching the core whereby the web is stuck to the core and the part of the web traveling away from the core is moved into contact with the knife and severed.

2. The method of transferring a moving flexible web running to a web roll being wound to a core to start the winding of another web roll which comprises moving the web approaching the web roll being wound over a support, bringing a rotatably mounted roll core into contact with the upper surface of the web on such support whereby the core is accelerated to web speed, positioning a knife across and adjacent the upper surface of the web where it passes from under the core and applying adhesive to the upper surface of the web approaching the core whereby the web is stuck to the core as it passes thereunder and the web leaving the core is lifted into the knife and severed.

3. The method of transferring a moving flexible web running to a web roll being wound to a core to start the winding of another web roll which comprises moving a web approaching the web roll being wound over a support that moves at substantially web speed, moving the cylindrical surface of a rotatable roll core into contact with the upper surface of the web on said support with the axis of the core extending transversely of the web whereby the core surface is accelerated to web speed, positioning a knife across and adjacent the upper surface of the web where it passes from under the core, and applying adhesive to the upper surface of the web approaching the core whereby the web is stuck to the core as it passes thereunder and the web beyond the core is lifted into the knife and severed.

4. The method of transferring a moving flexible

web running to a web roll being wound to a core to start the winding of another web roll which comprises moving a web approaching the web roll being wound over a support, bringing the cylindrical surface of a rotatable roll core carrying an applied and dried coating of, self-sticking adhesive into contact with the upper surface of the web on the support with the axis of the core extending transversely of the web whereby the core is accelerated to web speed, positioning a knife across and adjacent the upper surface of the web where it passes from under the core, and applying and drying a layer of self-sticking adhesive on the upper surface of the web approaching the core whereby when the adhesive layer carrying portion of the web passes under the core the web is stuck to the core and carried around the cylindrical surface thereof, and the web beyond the core is lifted into the knife and severed.

5. The method of transferring a moving flexible web running to a web roll being wound to a core to start the winding of another web roll which comprises bringing a rotatable roll core into contact with the surface of the web running to the roll whereby the core is accelerated to web speed, 20 positioning a knife across the web adjacent the core contacting surface of the web where it leaves the core, and applying adhesive to at least one of the contacting surfaces comprising the web and the core whereby the web is stuck to the core and the part of the web traveling away from the core is moved into contact with the knife and severed.

6. The method of severing a running web and starting the severed end thereof around a core to wind the web into a roll which comprises moving the cylindrical surface of a rotatable core into contact with the running web whereby the core surface is accelerated to web speed, holding the severing means across and close to the core contacting surface of the web leaving the core and applying adhesive to the core whereby the web is stuck to the core and the part thereof leaving the core is moved into the severing means and severed.

7. Apparatus for transferring a moving flexible web to a roll core to start the winding of a web roll while the web is traveling to a roll that is being wound comprising means for supporting the web traveling to the roll, means for rotatably supporting a roll core with its cylindrical surface in contact with the moving web on said support and its axis extending across the web, a knife extending across the web adjacent its core contacting surface and close to the point where the web leaves the core, and means for applying adhesive to the core contacting surface of the web approaching the core.

8. Apparatus for transferring a moving flexible web to a roll core to start the winding of a web roll while the web is traveling to a roll that is being wound comprising a surface moving at web speed for supporting the web traveling to the roll, means for rotatably supporting a roll core with its cylindrical surface in contact with the upper surface of the moving web on said moving surface and its axis normal to the path of travel of the web, a knife movable to a position adjacent the core and across the core contacting surface of the web leaving the core, means permitting limited movement of the core along the web in the direction of web travel, and means for applying adhesive to the core contacting surface of the web approaching the core.

9. Apparatus for transferring a moving flexible

web to a roll core to start the winding of a web roll while the web is traveling to a roll that is being wound comprising a rotating drum for supporting the web traveling to the roll being wound, means for rotatably supporting a roll core with its cylindrical surface extending across and in contact with the upper surface of the moving web on the drum, a knife adjacent the core extending across and close to the upper surface of the web leaving the core, means permitting limited movement of the core circumferentially of the drum in the direction of web travel, and means for applying adhesive to the upper surface of the web before it reaches the core.

10. Apparatus for transferring a moving flexible web to a roll core to start the winding of a web roll while the web is traveling to a roll that is being wound comprising a rotating drum for supporting the web traveling to the roll being wound, means for rotatably supporting a roll core with its cylindrical surface extending across and in contact with the upper surface of the moving web on the drum, a knife adjacent the core extending across and close to the upper surface of the web leaving the core, means permitting limited movement of the core circumferentially of the drum in the direction of web travel, and means for applying adhesive to the upper surface of the web before it reaches the core, and yielding tension means for the web approaching the drum for permitting limited changes in the speed of the web on the drum.

11. Apparatus for transferring a moving flexible web to a roll core to start the winding of a web roll while the web is traveling to a roll that is being wound comprising means for supporting the web traveling to the roll being wound, means for rotatably supporting a roll core with its cylindrical surface extending across and in contact with the upper surface of the web on the support, a layer of dried self-sticking adhesive on the cylindrical surface of the said core, a knife adjacent the core extending across the upper surface of the web leaving the core, and means for applying and drying a layer of self-sticking adhesive on the upper surface of a section of the web before it reaches the core.

12. Apparatus for transferring a moving flexible web to a roll core to start the winding of a web roll while the web is traveling to a roll that is being wound comprising a rotating drum for supporting the web traveling to the roll being wound, means for rotatably supporting a roll core with its cylindrical surface extending across and in contact with the upper surface of the moving web on the drum, a layer of dried self-sticking adhesive covering the cylindrical surface of said core, a knife adjacent the core extending across and close to the upper surface of the web leaving the core, means permitting limited movement of the core circumferentially of the drum in the direction of web travel, and means for applying and drying a layer of self-sticking adhesive on the upper surface of the web before it reaches the core.

13. Apparatus for transferring a moving flexible web to a roll core to start the winding of a web roll while the web is traveling to a roll that is being wound comprising a rotating drum for supporting the web traveling to the roll being wound, means for rotatably supporting a roll core with its cylindrical surface extending across and in contact with the upper surface of the

moving web on the drum, a layer of dried self-sticking adhesive covering the cylindrical surface of said core, a knife adjacent the core extending across and close to the upper surface of the web leaving the core, means permitting limited movement of the core circumferentially of the drum in the direction of web travel, means for applying and drying a layer of self-sticking adhesive on the upper surface of the web before it reaches the core, and yielding tension means for the web approaching the drum for permitting limited changes in the speed of the web on the drum.

14. Apparatus for transferring a moving flexible web to a roll core to start the winding of a web roll while the web is traveling to a roll that is being wound comprising means for supporting the web traveling to the roll, means for rotatably supporting a roll core with its cylindrical surface in contact with the moving web on said support and its axis extending across the web, a knife extending across the web adjacent its core contacting surface and close to the point where the web leaves the core, and means for applying adhesive to at least one of the contacting surfaces comprising the web and the core.

15. Apparatus for transferring a moving flexible web to a roll core to start the winding of a web roll while the web is traveling to a roll that is being wound comprising means for supporting the web traveling to the roll, means for rotatably supporting a roll core with its cylindrical surface in contact with the moving web on said support and its axis extending across the web, a knife extending across the web adjacent its core contacting surface and close to the point where the web leaves the core, and means for applying adhesive to the core.

16. The method of severing a running web and starting the severed end thereof around a core to wind the web into a roll which comprises moving the cylindrical surface of a rotatable core into contact with the running web whereby the core surface is accelerated to web speed, holding the severing means across and close to the core contacting surface of the web leaving the core and applying adhesive to the core contacting surface of the web approaching the core whereby the web is stuck to the core and the part thereof leaving the core is moved into the severing means and severed.

OSCAR C. ROESEN.
